(57) **CLAIM**

The ornamental design for a computer mouse, as shown and described.

DESCRIPTION

FIG. 1 is a rear elevation view of the computer mouse showing my new design;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top perspective view thereof.

The claimed computermouse is used in the design which looks like some offered cigarettes. The open package shows the cigarettes a little.

The computermouse is used with or without a cable between the computer and the computermouse. The computermouse as shown in the drawings is producible with or without invisible-, or slightly visible push-buttons and/or scroll-wheels. In the manufacturing process every technical configuration can be applied for the computermouse. The shape can have every ornament and/or print on every side.
